UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,329,001.

Specification of Letters Patent. Patented Jan. 27, 1920.

Application filed January 4, 1918. Serial No. 210,253.

To all whom it may concern:

Be it known that I, ERIC R. LUNDIUS, a citizen of the United States, residing at Brooklyn, in the county of Kings, State of New York, have invented certain new and useful Improvements in Telephone Systems, of which the following is a full, clear, concise, and exact description.

This invention relates to telephone systems and more particularly to such systems in which provision is made for signaling a telephone station which remains telephonically connected with the line after the termination of the conversation.

In such systems, heretofore employed means have been provided for connecting a source of signaling current to the line when at its minimum strength and then gradually increasing the current to a maximum strength, for causing the receiver connected with the line to produce a warning signal which gradually increases from a minimum to a maximum intensity. It is the object of the present invention to provide in a system of this character improved and simplified means for controlling the connection of the source of signaling current to the telephone line, whereby the chances for producing disagreeable and extremely intensive warning signals in a subscriber's ear are reduced to a minimum.

For a more complete understanding of the invention reference should be had to the following description considered in connection with the accompanying drawing illustrating one embodiment thereof.

There is shown in the drawing a telephone line A extending to and terminating at a central office at which is located a connecting circuit B. This connecting circuit B may be employed upon connection thereof with the telephone line to connect a source of signaling current with the line for causing the receiver at the station thereof when operatively connected with the line to produce a warning signal. Means for gradually varying the strength of the signaling current connected to the line comprises an induction coil 5 with whose primary winding may be connected a source of intermittent current derived from a battery and an interrupter 6. The secondary winding of the induction coil 5 is divided into sections the tap leads from which are successively connected with conductive segments of a

stationary ring 7 over which a brush 8 continuously rotates in the direction of the arrow. As this brush 8 rotates over the conductive segments of the ring 7 the number of secondary segments in circuit is gradually increased from a minimum to a maximum. This induction coil 5, having a divided secondary with which is associated the rotating brush 8, and the stationary ring 7 of conducting segments, comprises controlling means for gradually varying the strength of the signaling current connected to the line.

With this brief description of the apparatus shown in the drawing, it is thought that the invention may be best understood from a description of the operation of the system disclosed. If the receiver at station A remains removed from its switchhook at the termination of the conversation and after the withdrawal of the usual central office link circuit from its answering or multiple jack, line relay 10 will be operated and line lamp 11 lighted. An operator, upon connecting with this line, does not find a calling subscriber thereon, and therefore knows that the receiver has been left off the switchhook. Under such circumstances and in order that the subscriber may be signaled to restore the receiver to the switchhook, the operator disconnects from the line, and plug 15 of the connecting circuit B is then inserted into jack 16, whereupon relay 17 and cut-off relay 12 are operated. A connecting key 18 of the locking type is then actuated. Supervisory relay 19 is also operated upon the connection of the plug 15 with the jack 16 and in operating causes the energization of relay 20 over a circuit from battery through the contact of supervisory relay 19, the winding of relay 20, resistance 21, and the contact of relay 17 to ground. The winding of relay 20 is of such resistance that when connected in parallel with supervisory lamp 22 it provides a low resistance shunt, preventing the lighting of this lamp. The energization of relay 20 causes the opening of its contact, whereby a short circuit about the winding of relay 23 is removed. During this time brush 8 is rotating and when it reaches the position shown in the drawing, relays 17, 19 and 20 having previously operated, relay 23 is energized over a circuit from battery through resistance 24, the winding of relay 23, conductive segment 25 of the ring 7, the

brush 8, the upper contact of the key 18, and a winding of repeating coil 26 to ground. Relay 23 upon being energized connects battery and the interrupter 6 in 5 circuit with the primary winding of the induction coil 5, and establishes a locking circuit for itself from battery through the resistance 24, the winding and the upper contact of relay 23, the lower contact of the 10 key 18, and the contact of relay 17 to ground. Relay 23 thereafter remains energized independent of the position of the brush 8 with respect to the conductive segment 25 of the ring 7. The secondary of the 15 induction coil 5 is connected with the line through the upper and middle contacts of the actuated key 18. Intermittent current flowing through the primary winding of the induction coil 5 induces into the secondary 20 winding an alternating current, the effective strength of which is gradually increased due to the rotation of the brush 8, which gradually increases, from a minimum to a maximum, the number of the secondary sections 25 connected in the circuit. The signaling current so connected with the line causes the receiver at the station A to produce a warning signal, which gradually varies from a minimum to a maximum intensity. It is to be 30 observed that if the key 18 is actuated at the time the plug 15 is inserted into the jack 16 the energization of relay 23 serves to connect the source of signaling current with the telephone line. Since the closed primary circuit 35 can only be established when the brush 8 is on the conducting segment 25 and no sections of the secondary are in circuit, the warning signal produced by a receiver always begins at its minimum intensity. In 40 this manner loud and disagreeable clicks in the ear of a subscriber are prevented should the subscriber have the receiver to his ear at the time the warning signal starts.

The subscriber at station A having heard 45 the warning signal restores the receiver to the switchhook, thereby causing the deenergization of the supervisory relay 19, which releases its armature, removing the shunt from the lamp 22 which thereupon lights to furnish a signal to the operator. Relay 20 thereupon becomes deenergized and releases its armature, thereby short-circuiting the winding of relay 23 and causing the release thereof, which disconnects the source of 50 intermittent current from the primary winding of the induction coil 5. As long as the receiver remains on its switchhook the relay 20 remains deenergized, maintaining the short circuit about the relay 23; hence this 55 relay 23 can not be energized as long as the receiver remains on its switchhook. Therefore the signaling current can not be connected with the line. After once becoming deenergized, relay 23 can not be energized 60 again, even if the receiver is off its switch-

hook, until the rotating brush 8 again engages the conducting segment 25, at which time no portion of the secondary winding is connected with the line.

From this brief description it will be understood that should the subscriber upon hearing the warning signal produced by the receiver press down the switchhook to open the line circuit, at the same time placing the receiver to his ear and then immediately releasing the switchhook, no warning signal can be produced by the receiver until the brush 8 has again engaged the conducting segment 25. In other words the signaling current is disconnected from the line immediately upon the opening of the line at the subscriber's station and there is no possibility that the receiver will immediately thereafter produce a warning signal upon the closure of the telephone line. Therefore adequate protection is afforded subscribers who must be signaled in this manner when leaving the receiver removed from its switchhook.

What is claimed is:

1. A telephone system comprising a telephone line, a receiver connected therewith, a connecting circuit, a relay in the connecting circuit responsive to the connection thereof with the telephone line, a source of signaling current, a switching device for controlling the strength of the signaling current, a second relay whose energization is controlled by the response of the first relay for connecting the signaling current with the telephone line for causing the receiver to produce a warning signal, and a third relay controlled over the telephone line and deenergized by the opening thereof to cause the deenergization of the second relay.

2. A telephone system comprising a telephone line, a receiver connected therewith, a connecting circuit, a relay in the connecting circuit responsive to the connection thereof with the telephone line, a source of signaling current, a switching device for controlling the strength of the signaling current, a second relay whose energization is controlled by the response of the first relay for connecting the signaling current with the telephone line for causing the receiver to produce a warning signal, and a third relay controlled over the telephone line and deenergized by the opening thereof for disconnecting the signaling current from the line.

3. A telephone system comprising a telephone line, a receiver connected therewith, a connecting circuit, a relay in the connecting circuit responsive to the connection thereof with the telephone line, a source of signaling current, a switching device for controlling the strength of the signaling current, a second relay whose energization is controlled by the response of the first relay for connecting the signaling current

- with the telephone line for causing the receiver to produce a warning signal, a third relay controlled over the telephone line and deenergized by the opening thereof, and a short circuit for the second relay controlled by the deenergization of the third relay.
4. A telephone system comprising a telephone line, a receiver connected therewith, a connecting circuit, a relay in the connecting circuit energized over the telephone line when connection is made therewith, a source of signaling current, a switching device for controlling the strength of the signaling current, a second relay for connecting the source of signaling current with the telephone line for causing the receiver to produce a warning signal, and an energizing circuit for the second relay controlled by the control switching device and the first relay and established when the control switching device is in a particular position and when the first relay is energized.
5. A telephone system comprising a telephone line, a receiver connected therewith, a connecting circuit, a relay in the connecting circuit energized over the telephone line when connection is made therewith, a source of signaling current, a switching device for controlling the strength of the signaling current, a second relay for connecting the source of signaling current with the telephone line for causing the receiver to produce a warning signal, an energizing circuit for the second relay controlled by the control switching device and the first relay and established when the control switching device is in a particular position and when the first relay is energized, and a locking circuit for the second relay established by the energization thereof for rendering this relay independent of the control switching device.
6. A telephone system comprising a telephone line, a receiver connected therewith, a connecting circuit, a relay in the connecting circuit energized over the telephone line when connection is made therewith, a source of signaling current, a switching device for controlling the strength of the signaling current, a second relay for connecting the source of signaling current with the telephone line for causing the receiver to produce a warning signal, an energizing circuit for the second relay controlled by the control switching device and the first relay and established when the control switching device is in a particular position and when the first relay is energized, and means for deenergizing the second relay controlled by the deenergization of the first relay.
7. A telephone system comprising a telephone line, a receiver connected therewith, a connecting circuit, a relay in the connecting circuit energized over the telephone line when connection is made therewith, a source of signaling current, a switching device for controlling the strength of the signaling current, the strength of the signaling current, a second relay for connecting the source of signaling current with the telephone line for causing the receiver to produce a warning signal, an energizing circuit for the second relay controlled by the control switching device and the first relay and established when the control switching device is in a particular position and when the first relay is energized, and a third relay for connecting the source of signaling current with the telephone line for causing the receiver to produce a warning signal, an energizing circuit for the third relay controlled by the second relay and es-
- controlling the strength of the signaling current, a second relay for connecting the source of signaling current with the telephone line for causing the receiver to produce a warning signal, an energizing circuit for the second relay controlled by the control switching device and the first relay and established when the control switching device is in a particular position and when the first relay is energized, and a short circuit for the second relay controlled by the deenergization of the first relay.
8. A telephone system comprising a telephone line, a receiver connected therewith, a connecting circuit, a relay in the connecting circuit energized over the telephone line when connection is made therewith, a source of signaling current, a switching device for controlling the strength of the signaling current, a second relay for connecting the source of signaling current with the telephone line for causing the receiver to produce a warning signal, an energizing circuit for the second relay controlled by the control switching device and the first relay and established when the control switching device is in a particular position and when the first relay is energized, a locking circuit for the second relay established upon the energization thereof for rendering this relay independent of the control switching device, and a circuit controlled by the deenergization of the first relay for rendering the locking circuit ineffective and for preventing the reenergization of the second relay.
9. A telephone system comprising a telephone line, a receiver connected therewith, a connecting circuit, a relay responsive to the connection thereof with the telephone line, a second relay energized over the connected telephone line, a source of signaling current, a switching device for controlling the strength of the signaling current, a third relay for connecting the source of signaling current with the telephone line for causing the receiver to produce a warning signal, and an energizing circuit for the third relay controlled by the second relay and established by the response of the first relay when the control switching device is in a particular position and when the second relay is energized.
10. A telephone system comprising a telephone line, a receiver connected therewith, a connecting circuit, a relay responsive to the connection thereof with the telephone line, a second relay energized over the connected telephone line, a source of signaling current, a switching device for controlling the strength of the signaling current, a third relay for connecting the source of signaling current with the telephone line for causing the receiver to produce a warning signal, an energizing circuit for the third relay controlled by the second relay and es-

tablished by the response of the first relay when the control switching device is in a particular position and when the second relay is energized, and a locking circuit for the third relay controlled by the energization thereof for rendering this relay independent of the control switching device and including a contact of the first relay.

11. A telephone system comprising a telephone line, a receiver connected therewith, a connecting circuit, a relay responsive to the connection thereof with the telephone line, a second relay energized over the connected telephone line, a source of signaling current, a switching device for controlling the strength of the signaling current with the telephone line for causing the receiver to produce a warning signal, a third relay,

an energizing circuit for the third relay controlled by the second relay and established by the response of the first relay when the control switching device is in a particular position and when the second relay is energized, a locking circuit for the third relay controlled by the energization thereof for rendering this relay independent of the control switching device and including a contact of the first relay, 20
